UNITED STATES PATENT OFFICE.

FRIEDRICH YOSI, OF UTICA, NEW YORK.

STEAMING-TABLE.

No. 910,629.

Specification of Letters Patent.

Patented Jan. 26, 1909.

Application filed September 26, 1906. Serial No. 336,239.

To all whom it may concern:

Be it known that I, FRIEDRICH YOSI, of Utica, in the county of Oneida and State of New York, have invented certain new and 5 useful Improvements in Steaming-Tables; and I do hereby declare that the following is a full, clear, and exact description thereof, which will enable others skilled in the art to which it appertains to make and use the 10 same, reference being had to the accompanying drawings, and to the letters of reference marked thereon, which form part of this specification.

The object of my invention is to provide a 15 portable compact steaming table or device complete in itself for moistening and heating garments in connection with cleaning and pressing them or otherwise.

Figure 1 shows a side elevation of my device. Fig. 2 shows an end view of the same. Fig. 3 shows a vertical central section. Fig. 4 shows a partial top view and a partial sectional view.

Referring to the reference letters and figures in a more particular description, 1 indicates the table, which is of elongated form and provided with a perforated and preferably crowning top 1^a and a convex bottom 1^b. The table 1 is mounted on a frame work 2, whereby it is supported at suitable elevation for convenient use, and the ends of the table overhang the frame at either end to some extent, whereby a garment can be placed thereon to better advantage. Beneath the table and within the frame 2, there is provided a boiler 3. The interior of the table 1 is divided into two chambers by a cross partition 1^c, and the boiler 3 is connected by steam pipes 4 with these two 30 chambers, the pipes 4 branching and being provided with valves 5—5, whereby either section of the chamber in the table may be shut off from the boiler. The boiler is also supported by the pipes 4. An upright pipe 6 35 is provided communicating with the boiler at the lower end, and provided with a funnel at the upper end whereby water can be readily introduced into the boiler, and 7 is a water glass by means of which the height of 40 the water in the boiler can be observed. A gas or gasoline torch or burner 8 is provided under the boiler for producing heat to gener-

ate steam in the boiler, although any other suitable heat producing means may be provided.

When in use the perforated top of the table is preferably covered with cloth, and the garment to be operated upon is placed on top of the table and the cloth thereon. The steam from the boiler passes into either or both the 55 chambers of the table and out through the perforations in the top, and moistens and heats the garment placed on the upper surface of the table, which may be operated upon at the same time for cleaning, pressing or otherwise.

In case the entire perforated surface of either end of the table is not in use, the escape of steam and heat therefrom will be substantially shut off by an impervious blanket of 60 rubber, cloth or other suitable material. When the two valves 5 are open both ends of the 65 table can be used simultaneously, or by closing either of these valves one-half of the table may be used in the steaming and heating 70 operation.

As will be seen the two overhanging ends of the table provide a plurality of garment receiving portions to which, by virtue of the partition 1^c and valves 5, steam may be independently admitted. This construction permits a plurality of garments to be moistened and heated by the table at the same time, whereby while one garment is being cleaned or pressed another may be in course 75 of preparation for such operation.

The arrangement of the boiler 3 beneath the table and its connections with the two chambers in the table are such that the condensation from the steam in the chambers 80 will return through the pipes into the boiler. The concave form of the bottom and the taper towards the ends of the table facilitate this return, as well as gives general strength 85 to the construction.

What I claim as new and desire to secure by Letters Patent is:

The combination, in a device of the character described, of a supporting frame, a hollow elongated steaming table having a perforated top mounted on and supported by the frame and having two overhanging garment-receiving ends, a substantially central partition within said table, dividing the same

into two chambers, one corresponding with each of said garment-receiving ends, a steam pipe having a branch leading to each of said chambers and into which steam pipe both of said chambers are adapted to drain, independently operable valves in said branches, and a steam boiler within said frame and supported by said steam pipe, and which latter forms a communication between said cham-

ber and the interior of said boiler, substantially as set forth.

In witness whereof, I have affixed my signature, in presence of two witnesses, this 19th day of September 1906.

FRIEDRICH YOSL
